UNITED STATES PATENT OFFICE.

PETER J. KING, OF MILWAUKEE, WISCONSIN.

PIPE CUTTER.

1,413,228.

Specification of Letters Patent. Patented Apr. 18, 1922.

Application filed June 2, 1921. Serial No. 474,417.

To all whom it may concern:

Be it known that I, PETER J. KING, a citizen of the United States, and resident of Milwaukee, in the county of Milwaukee, 5 and State of Wisconsin, have invented certain new and useful Improvements in Pipe Cutters; and I do hereby declare that the following is a full, clear, and exact description thereof.

10 My invention relates to a new and improved pipe cutter which is more specially adapted for cutting soil pipe after it has been installed.

In the construction of modern buildings 15 in which the bath room is usually finished with a cement or tile floor, it is necessary to set the soil pipe in position before the floor is finished. It has been the custom to cut the soil pipe at the proper length 20 before it is connected. This has caused considerable dissatisfaction since the cement or tile workers cannot always be depended upon to finish the floor at the level which has been planned by the plumber, and as a 25 consequence the pipe will be too short or too long.

It is the principal object of my invention to provide a practical device by which the end of the pipe may be cut off after 30 the floor has been completed.

It is a further object of the invention to provide suitable means by which the point at which the pipe is cut may be accurately determined.

35 A still further object of the invention is to provide means for facilitating the removal of the tool from the pipe after the cutting operation has been completed.

With the above and other objects in view, 40 which will be apparent from the following description, the invention consists in certain details which will be described in connection with the accompanying drawing in which,

45 Figure 1 is a vertical transverse section through the tool disposed in operative position.

Figure 2 is a sectional plan view on the line 2—2 of Figure 1.

50 Figure 3 is a sectional plan view on the line 3—3 of Figure 1.

The tool which comprises my invention is supported by the frame or tripod 5 which rests upon the floor surrounding the pipe, 55 as shown at 6. A sleeve 7 is supported in the tripod and may be secured in adjusted

position by any suitable means, as for example,—the set screw 7^a. The lower end of the sleeve 7 is provided with a peripheral flange 8 which engages the inwardly extending lip 9 of an annular plate or disk 10, whereby the plate is revolubly supported. A cylindrical block, which, in the present instance is composed of three sections, 11, 11^a and 11^b, is supported by the plate 10, 60 each section being provided with a screw 12 which is tapped into the upper end of the section and slidably secured in the slot 13. Each section is also provided with a screw 14 on which is rotatably mounted 70 a cutter 15. The sections of the block are held by the springs 16 and 17, which are tensioned so as to urge the sections towards their innermost position. Extending axially of the block is a tapered opening which 75 receives the tapered core 18, the several sections of the block being keyed to the core by means of a key 19. The core 18 is provided with a stem 20 which projects upwardly through the sleeve 7 and is provided with a non-circular portion 21 on 80 which is fitted the handle 22. A washer 23 may be provided between the handle and the end of the sleeve 7. In order to move the core upwardly and expand the 85 block, the upper end of the stem is threaded, as shown at 24 and provided with a wing nut or the like, 25. In the operation of my device, the core 18 is lowered by unscrewing the nut 25 sufficiently to permit the block 90 to be inserted in the end of the pipe. The sleeve 7 is then adjusted vertically to bring the cutting element to the point at which it is desired to cut the pipe and the sleeve 95 is secured in this position by means of the 95 set screw 7^a. The cutters are then re-set, as it will be readily understood, by means of the handle 22 and from time to time the block is expanded by turning up the screw 25 in the usual manner. This 100 operation is continued until the cutting is completed. The screw 25 may then be turned to release the core 18 and permit the block to contract. It will be seen, however, that owing to the force exerted 105 in cutting the pipe, the core will be wedged tightly in the block. In order to facilitate its removal from the pipe, an upward pull may be exerted on the sleeve 7 or the tripod after the nut 25 has been loosened. At the 110 same time it may be desirable to deliver a slight blow on the end of the stem. This

will at once result in the block moving upwardly in respect to the core and consequently permit the same to contract under the influence of the springs 16 and 17, 5 and thus be readily removed.

While I have shown the ribs 19 midway of the respective sections it may be advisable to locate them at the edges of the 10 sections to permit a relatively larger cutting element to be used. The vertical dimensions of the sections should be relatively short so as to permit the use of the device where there is an elbow in the pipe immediately below the floor. It will be understood 15 that the structure herein described is for the purpose of illustration only and that my invention comprises all equivalents which are included within the scope of the appended claims.

20 I claim:

1. A pipe cutting tool for cutting soil pipe and the like, comprising a supporting frame adapted to rest upon the floor, a vertically disposed sleeve adjustably supported in said frame, a cylindrical block 25 revolvably supported at the lower end of the sleeve and provided with cutting elements, said block being composed of sections, each radially movable with respect 30 to the sleeve, resilient means for normally holding said sections in their innermost

positions, said block being formed with a tapered bore, a tapered expanding member adapted to be received in said bore and having a stem extending through said 35 sleeve, means for moving said expanding member longitudinally to force the sections of the block outwardly and means for rotating said block to render the cutting elements operative.

2. A pipe cutting tool for cutting soil pipe after it has been installed comprising an expansible cylindrical block adapted to be inserted in the pipe, said block being divided radially into a plurality of sections, a channel extending circumferentially around the block, means for supporting and guiding the sections for radial movement, a circular spring seated in the channel and urging the sections inwardly, cutting elements carried by the several sections, means for supporting the block at a predetermined height in the pipe, means for rotating the same, and means for forcing the sections outwardly against the resistance of the 55 spring.

In testimony that I claim the foregoing I have hereunto set my hand at Milwaukee, in the county of Milwaukee and State of Wisconsin.

PETER J. KING.
